(57) **CLAIM**

The ornamental design for microscope stand, as shown and described.

DESCRIPTION

FIG. 1 is a perspective view of a microscope stand of the invention;

FIG. 2 is a front view of the microscope stand of FIG. 1;

FIG. 3 is a right side view of the microscope stand of FIG. 1;

FIG. 4 is a left side view of the microscope stand of FIG. 1;

FIG. 5 is a top view of the microscope stand of FIG. 1;

FIG. 6 is a bottom view of the microscope stand of FIG. 1;

and,

FIG. 7 is a rear view of the microscope stand of FIG. 1.

APPLICATION NO. : 29/218412

DATED : April 11, 2006

INVENTOR(S) : Christophe Apotheloz and Oliver Jagemann

It is certified that error appears in the above-identified patent and that said Letters Patent is hereby corrected as shown below:

The Title page, showing an illustrative figure, should be deleted and substitute therefor the attached Title page.

Delete drawing sheets 1-7 and substitute therefor the attached Amended Drawings, Figures 1-7.

Signed and Sealed this

Ninth Day of September, 2008

JON W. DUDAS
Director of the United States Patent and Trademark Office
